(57) **CLAIM**

I claim the ornamental design for electric connector cord, as shown and described.

DESCRIPTION

FIG. 1, is a front view of the ornamental design for electric connector cord, and the back view is a mirror image of FIG. 1,

FIG. 2, is a left side view thereof, and the right side is a mirror image of the left side FIG. 2,

FIG. 3, is a top end view thereof, and the bottom end view is a mirror image of the top end view shown in FIG. 3; and, FIG. 4, is a perspective view of the ornamental design for electric connector cord.

The claimed design in FIGS. 1, 2, and 4 is shown broken away to indicate indeterminate length.

1 Claim, 2 Drawing SheetsFIG. 1

FIG. 2

FIG. 3

FIG. 4
